United States Patent Office.

A. C. HOBBS, OF BRIDGEPORT, CONNECTICUT.

Letters Patent No. 85,823, dated January 12, 1869.

IMPROVEMENT IN WAD-GREASING APPARATUS.

The Schedule referred to in these Letters Patent and making part of the same.

To all whom it may concern:

Be it known that I, A. C. HOBBS, of Bridgeport, in the county of Fairfield, and State of Connecticut, have invented certain new and useful Improvements in Machinery for Greasing Gun-Wads; and I do hereby declare that the following is a full, clear, and exact description thereof, reference being had to the accompanying drawings, making part of this specification, and to the letters of reference marked thereon; like letters indicating like parts wherever they occur.

To enable others skilled in the art to construct and use my invention, I will proceed to describe it.

My invention consists in a novel construction of an apparatus for greasing gun-wads as they are cut from the sheet, and in so applying the grease to the wads as that they shall be greased or saturated around their edge or periphery only, as hereinafter more fully explained.

Figure 1 is a longitudinal vertical section,

Figure 2 is a top plan view, and

Figure 3 is a face view of a wad, completed.

To make my improved apparatus, I provide a metallic bed-piece, A, and form a recess or cavity, B, in its upper face, as represented in fig. 1, this cavity thus forming a cup or receptacle for the grease, or lubricating-material.

In order to keep the grease melted, or in a fluid state, I form a cavity or passage, C, in the raised portion of the plate A, surrounding the cup B, into which a current of steam is admitted at one end, from whence it passes around the cup, and escapes at the opposite side of the same end at which it entered, as indicated by the dotted lines and arrows in fig. 2.

Through the bottom of the cup B, I make a series of holes, and secure therein tubes D, corresponding in diameter, internally, with the diameter of the wads to be greased; these tubes D, having a series of horizontal slits, a, cut in them, just above the bottom of the cup B, as shown in fig. 1.

The cutters, consisting of a series of steel tubes or punches, I, are secured in a plate, E, which rests upon the bed-plate A, over the cup B, where it is secured by a wedge, o, as shown in fig. 2, or in any suitable manner, the punches I being placed directly over the tubes D, the two thus forming continuous tubes, as represented in fig. 1.

To secure accuracy in this respect, the upper ends of the tubes D are permitted to extend a short distance up into the plate E, where they abut against the lower ends of the punches I.

These devices, thus constructed, constitute the improvements contained in my apparatus.

In using it, the sheet of material from which the

wads are cut, are fed along by feed-rolls, over the top of the punches, with an intermittent motion, a platen or follower being pressed down upon the sheet from above, and thus forcing the sheet down upon the punches, and cutting out the wads.

As usual, in this class of wad-cutters, there is a perforated plate fitted around the punches I, and resting on springs, which latter, as soon as the pressure from above is removed, elevate the plate even with the top of the punches, thereby raising the sheet up off the punches, so that it can be fed along for another cut, and so on continuously.

These features being well known, and in common use, need not be herein further described.

The operation is as follows:

The sheet being fed along, and the wads continuously or successively cut therefrom, are forced down into the tubes D, as indicated by the blue lines on the left-hand tube of fig. 1. As the wads are thus forced down, the grease runs through the slits a, and, coming in contact with the edges of the wads, greases them, one after another, as they pass down by the slits a, the wads being forced out at the lower open ends of the tubes D.

It will be observed that the slits a are arranged in two rows, in such a manner as to break joints, the slits in one row coming opposite the spaces between the slits in the other row, so as to permit the grease to flow through all around, and thus come in contact with the entire periphery of the wad.

By this arrangement, there is just enough grease used to thoroughly grease the entire edge of the wad, without saturating the entire body, the greased part thus forming a ring around the outer edge of the wad, as indicated, or shown in fig. 3, the colored portion representing the greased part, thus greasing only that part required, and effecting a great economy of the lubricating-material, as well as of the labor necessary to perform the operation.

Having thus described my invention,

What I claim, is—

1. The plate A, provided with the reservoir for containing the grease, and the steam-passage C, for keeping the same warm, or in a fluid state, and the perforated tubes D, when arranged to operate substantially as and for the purpose herein described.

2. The combination of the plate A, constructed as above described, with the plate E, having the punches I secured therein, substantially as set forth.

A. C. HOBBS.
